TABLE

Joseph E. Kienel, P.O. Box K, Acworth, Ga. 30101

Filed Apr. 26, 1971, Ser. No. 137,748

Term of patent 14 years

Int. Cl. D6—03

U.S. Cl. D6—146

FIG. 1 is an isometric view of a table of my instant design; and

FIG. 2 is an enlarged sectional view taken substantially along line 2—2 in FIG. 1.

The reverse side of the table of my instant design is substantially the same as that shown in FIG. 1.

I claim:

The ornamental design for a table, substantially as shown and described.
